UNITED STATES PATENT OFFICE.

KENNETH J. TOBIN, AXEL WASBERG, AND GABRIEL MADLAND, OF CHICAGO, ILLINOIS,
ASSIGNORS TO CAMEL COMPANY, OF CHICAGO, ILLINOIS, A CORPORATION OF
ILLINOIS.

HOUSE CAR.

Application filed May 26, 1927. Serial No. 194,266

This invention relates to a house car for railroads having a sliding door and concerns itself primarily with cooperating means between the door and car for causing said door to move outwardly clear of the side of the car and substantially parallel thereto when the same is opened. This feature of construction prevents scraping between the door and side of the car, eliminates injury to the parts and makes it easier to operate the door.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a fragmentary side elevational view of a house car involving this invention.

Figure 2 is an enlarged fragmentary sectional view taken upon the line II—II of Figure 1.

Figure 3 is an enlarged fragmentary sectional view taken upon the line III—III of Figure 1.

Figures 4, 5 and 6 are views similar to Figure 3 illustrating modified forms of tracks that may be used.

Figure 7 is a view similar to Figure 3 illustrating a modification in which the indenture on the door is in reversed form.

Figure 8 is an enlarged broken sectional view taken on the line VIII—VIII of Figure 1.

Figure 9 is a view similar to Figure 8 but showing the door in partly open position.

As shown on the drawings:

In order to illustrate and explain this invention, there is shown a portion of a house car 1 having a sliding door 2 for closing the doorway thereof. At one margin of the doorway, there is a supporting track 3 which in the present instance is shown adjacent the lower margin of the doorway. The sliding door 2 is sustained upon said track by suitable rollers 4 supported in roller housings 4^a on the door.

The door is guided upon the track 3 by an upper guide 5 and a lower guide 6 (Figure 3). The upper guide 5 preferably consists of an angular member having a depending flange 5^a as shown more clearly in Figure 2

which extends into a pair of narrow guide channels 7 at the upper margin of the door. The lower guide 6 is preferably a vertical flange formed integrally with the track 3 as shown in Figure 3 and 60 which extends into guideways 8 formed between the lower portion of the door proper and the inner wall 9 of the roller housings 4^a.

The cooperating means between the door and car for the purpose of moving the door outwardly and free of the side of the car when the same is opened as shown in Figure 9 may assume various forms. The preferred form, however, consists of a pair of spaced indentures 10 upon the upper guide 5 as 70 shown in Figure 2 and a pair of spaced indentures 11 on the lower guide 6 in combination with suitable indenture means 12 extending from the side walls 9 of the roller housing. The indenture means 12 are shown 75 as consisting of inwardly extending convex projections or humps which are designed to enter the indentures 11. The front indenture 10 is preferably in vertical alinement with the front indenture 11 and the rear indentures 10 and 11 are also preferably in vertical alinement so that the upper and lower portions of the door will simultaneously be moved inwardly. It will be noted that the indentures in the guides 5 and 6 are so located 80 as to receive the indenture means 12 and guide channels 7 when the door is closed.

It will be noted that the upper guide channels 7 on the door are sufficiently narrow to enter the indentures 10. The lower margin 90 of the door in the preferred form is inwardly offset as indicated at 13 except at the points 14 which are directly opposite the convex indentures or humps 12. This offset 13 allows for the outward movement of the 95 door as shown in Figure 9.

The front edge of the door is provided with an angular weather strip 15 which engages under the angular weather strip 16 on the door jamb. The rear end of the door has an angular weather strip 17 that cooperates with the angular weather strip 18 on the rear door post. The front indentures in the upper and lower guides are so designed that they will guide the front weather strip 15 under the outer flange of the weather strip 16 as shown in Figure 8.

In the modifications shown in Figures 4, 5, 6, the door 2, rollers 4 and housing 4^a are the same as in the preferred form. 110

The only difference exists in the supporting track for the door. In Figure 4 the track 3^a has the guide flange 6, but said track is provided with a depending rim 19 for shedding the weather. In Figure 5, the track 3^b has a depending flange 20, spaced inwardly from the outer edge of the track. In Figure 6 the track 3^c has a channel formation below the guide flange 6.

10 In Figure 7 there is shown a track 3^d having the vertical guide flange 6, and a depending flange 21 which rests upon a shoulder 22 of the supporting bracket 23. It might be mentioned that these various forms
15 of tracks are usually supported upon suitable brackets extending from the side sill 24 of the car.

In Figure 7 the door 2^a does not have its lower margin inwardly offset as in the preferred form. This lower margin, however, has outwardly extending indentures 25 opposite the convex humps 12 on the inner wall 9 of the roller housing. It will be obvious that these indentures consisting of the parts
25 25 and 6 will cause the door to move outwardly when the same is opened. It should be understood that the term indenture is broadly used to include not only the indentures 10 on the upper and lower guides, but
30 also those parts on the door, for example the parts 12 and 25 that cooperate therewith.

When the door is in its closed position, the guide channels 7 and the indenture means on the door are in the indentures of the
35 guides as shown in Figure 8. Now when the door is opened, the indenture means 12 and the guide channels 7 will slide or move out of the indentures and force the door to move outwardly free of the side of the car
40 as shown in Figure 9. Consequently when the door is slid rearwardly beyond its open-

ings, it will not scrape or injure the side of the car. At the same time, any binding of the door will be eliminated.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. In a house car having a doorway, a sliding door for closing said doorway, upper and lower guides and sustaining means for said door, each guide having spaced indentures and said door having means adapted for entering said indentures when said door is closed, said means riding out of said indentures and moving the door outwardly when the same is opened.

2. In a house car having a doorway, a track having a vertical flange adjacent one margin of the doorway, a guide upon the opposite margin of the doorway, a sliding door on said track and guided by said guide, said flange and guide having spaced indentures and said door having means entering said indentures when the same is closed.

3. In a house car having a doorway, a track adjacent one margin of the doorway, a sliding door on said track, a guide for the door adjacent said track, said door and guide having spaced indentures adapted for causing the door to move outwardly when the same is opened.

In testimony whereof, we have hereunto subscribed our names.

KENNETH J. TOBIN.
AXEL WASBERG.
GABRIEL MADLAND.
